APPLIANCE-HOLDING BRACKET

Harris B. Mandel, New York, N.Y., assignor to Bright Star Industries Incorporated, Clifton, N.J., a corporation of Delaware

Filed Jan. 14, 1969, Ser. No. 15,333

Term of patent 3½ years

Int. Cl. D8—03
U.S. Cl. D8—233

FIG. 1

FIG. 3

FIG. 1 is a perspective view of an appliance-holding bracket showing my new design;

FIG. 2 is a rear elevational view of the bracket of FIG. 1; and

FIG. 3 is a bottom plan view of the bracket of FIG. 1.

I claim:

The ornamental design for an appliance-holding bracket, as shown.
